UNITED STATES PATENT OFFICE.

FREDRICK THOS. SMITH, OF SOMERSET, PENNSYLVANIA.

ASH-TRAY HOLDER.

Application filed December 29, 1923. Serial No. 683,468.

To all whom it may concern:

Be it known that I, FREDRICK T. SMITH, a citizen of the United States, residing at Somerset, in the county of Somerset and 5 State of Pennsylvania, have invented new and useful Improvements in Ash-Tray Holders, of which the following is a specification.

This invention relates to ash tray devices 10 and has for its object the provision of a novel ash tray, or holder therefor, so constructed and designed as to be used upon the arm of a rocking chair, the arrangement being such that the ash tray carried by 15 the holder will remain always in upright or proper position regardless of how violently the chair may be rocked so that spilling of the ashes will be prevented.

An important and more specific object is 20 the provision of a holder which is weighted so that it will remain always in a certain position, this holder further including an attaching bracket to which the holder proper is rotatably mounted.

25 An additional object is the provision of a device of this character which will be simple and inexpensive to manufacture, easy to install, positive in action, neat in appearance, efficient and durable in service and 30 a general improvement in the art.

With the above and other objects and advantages in view the invention consists in the details of construction to be hereinafter more fully described and claimed and illustrated in the accompanying drawings, in 35 which:

Figure 1 is a plan view of the device showing it mounted upon the arm of a rocking chair,

40 Figure 2 is an elevation of the device showing it applied to the arm,

Figure 3 is a cross section through the holder,

45 Figure 4 is a detail perspective view of the attaching bracket alone.

Figure 5 is a view showing a slight modification.

Referring more particularly to the drawings I have shown my device as comprising 50 an attaching bracket 10 formed preferably from a single piece of sheet metal bent to shape and including a base portion 11 from which extend spaced ears 12. The base is formed with suitable holes 13 for the passage of securing screws by means of which the bracket may be mounted either upon the

top or underneath the arm A of a rocking chair or the like. Naturally it is preferable that the bracket be mounted on the underside as it will then be ordinarily concealed from view. 60

The device further includes an arm 14 which in actual practice may conveniently be formed from a single piece of heavy wire or light rod of any proper gage, this arm including a shank 15 rotatably engaged through the ears 12 and provided at its end with an enlargement 16 which may be integral or attached and which is for the purpose of preventing withdrawal of the shank 65 from engagement with the bracket. This arm further includes a ring portion 17 within which is suitably secured a cup 18 which has its bottom 19 heavily weighted. Obviously, if preferred, the cup may simply 70 be cast with an arm thereon rotatable through the ears, there being no limitation in this respect as such would be merely a matter of mechanical construction. 75

In case it is undesirable to screw or 80 otherwise fasten the holding bracket to the arm of the chair, use may be made of the clamp 20 illustrated in Figure 5, which clamp takes the place of the above described bracket and is formed with spaced ears 21 85 through which the arm 14 passes.

The cup is intended to support a conventional ash tray B which is simply set thereinto but it is of course apparent that the cup itself might be formed as an ash tray 90 if preferred.

In the operation it is evident that when a smoker seated in the rocking chair rocks back and forth, the weighted cup will remain always in horizontal or normal position no matter how violently the chair is rocked, the shank 15 turning within the bracket ears. In this way there will be no possibility of spilling the ashes. 95

From the foregoing description and a 100 study of the drawings it will be apparent that I have thus provided a very simple, inexpensive and efficient device for the purpose specified which will not only be neat and attractive in appearance but which will 105 also act positively to save soiling of the floor or floor covering.

While I have shown and described the 110 preferred embodiment of my invention it is of course to be understood that I reserve the right to make such changes in the form, construction and arrangement of parts as

will not depart from the spirit of the invention or the scope of the subjoined claim.

Having thus described my invention I claim:

5 In a device of the character described, a U-shaped bracket adapted to be mounted upon the under side of a chair arm or equivalent support and including space depending arms having aligned holes there-
10 through, a rod journaled through the holes in said arms and terminating at one end in

a ring, means on said rod engaging outwardly of said spaced arms for preventing longitudinal displacement of the rod, a tray removably engaged within said ring and 15 having a weighted bottom whereby to remain normally in upright position, the rotatability of the rod through said bracket arm permitting dumping of the tray.

In testimony whereof I affix my sig- 20 nature.

FREDRICK THOS. SMITH.
